(57) **ABSTRACT**

Disclosed is an electronic timepiece, comprising: hands which indicate time to display the time; a stepping motor which performs a stepping drive of the hands; a drive control section which supplies the stepping motor with drive pulses; a hand movement examining section which examines whether the hands are moving or not; and awaiting control section which temporarily interrupts a supply of the drive pulses by the drive control section to be in a waiting state, when the hand movement examining section judges that the hands are stopped, wherein the supply of the drive pulses by the drive control section and an examination of whether the hands are moving or not by the hand movement examining section are respectively restarted, after the waiting control section has released the waiting state.

ELECTRONIC TIMEPIECE

CROSS-REFERENCE TO RELATED
APPLICATIONS

This application is based upon and claims the benefit of priority under 35 USC 119 of Japanese Patent Application No. 2010-091112 filed on Apr. 12, 2010, the entire disclosure of which, including the description, claims, drawings, and abstract, is incorporated herein by reference.

BACKGROUND OF THE INVENTION

1. Field of the Invention

The present invention relates to an electronic timepiece displaying time with hands and being equipped with a hand position detecting mechanism.

2. Description of Related Art

In an electronic timepiece driving its hands with a stepping motor, for example, if a strong magnet is situated in the vicinity of the electronic timepiece, the rotor of the stepping motor does sometimes not rotate although drive pulses are supplied, and the hands are not driven.

An electronic timepiece equipped with a function of detecting the positions of its hands has conventionally been proposed (see, for example, Japanese Patent Application Laid-Open Publication No. 2009-085674), which timepiece detected the positions by forming a penetration hole in each of the gears rotating in conjunction with the hands, respectively, and setting the penetration holes to appear at a detection position when the hands were situated at a predetermined position to detect the penetration holes with a photointerrupter or the like and thereby to detect the positions of the hands.

There can be a case where stops of the hands owing to an external factor extend over a long period of time, for example, a case where an electronic timepiece is left as it is in the neighborhood of a strong magnet. In this case, if the position detection of the hands is continuously being performed from the detection of the stops of the hands to the detection of the next rotations of the hands while supplying the stepping motor with drive pulses, the output of the drive pulses and the position detection of the hands are uselessly executed many times to cause a remarkable increase of power consumption.

The present invention provides an electronic timepiece equipped with a hand position detecting mechanism which electronic timepiece can suppress the remarkable increase of the power consumption thereof at the time of stops of the hands thereof.

SUMMARY OF THE INVENTION

According to an aspect of the present invention, there is provided an electronic timepiece, comprising:

hands which indicate time to display the time;

a stepping motor which performs a stepping drive of the hands;

a drive control section which supplies the stepping motor with drive pulses;

a hand movement examining section which examines whether the hands are moving or not; and

a waiting control section which temporarily interrupts a supply of the drive pulses by the drive control section to be in a waiting state, when the hand movement examining section judges that the hands are stopped, wherein

the supply of the drive pulses by the drive control section and an examination of whether the hands are moving or not by

2

the hand movement examining section are respectively restarted, after the waiting control section has released the waiting state.

5 BRIEF DESCRIPTION OF THE DRAWINGS

FIG. 1 is a block diagram showing the whole of an electronic timepiece of an embodiment of the present invention;

10 FIG. 2 is a diagram showing counters and a data storing section formed in a RAM;

FIG. 3 is a front view showing a train wheel mechanism included in the analog block of FIG. 1;

15 FIG. 4 is a sectional view showing an arrangement relation between a first detection wheel, a second detection wheel, and a photodetector;

FIG. 5 is a first part of a flow chart showing a control procedure of hand position examining processing executed by a central processing unit (CPU);

20 FIG. 6 is a second part of the flow chart showing the same hand position examining processing;

FIG. 7 is a third part of the flow chart showing the same hand position examining processing;

25 FIGS. 8A, 8B, 8C, 8D and 8E are a first part of explanatory views showing an operation of a hand position examination at the time of a normal hand movement;

FIGS. 9A, 9B, 9C, 9D, and 9E are a second part of the explanatory views showing the operation of the same hand position examination at the time of the normal hand movement;

30 FIG. 10 is an explanatory view showing a state when a hand shift is detected in the hand position examination;

FIGS. 11A and 11B are explanatory views showing a state when the hands abnormally stop at a detection position;

35 FIGS. 12A and 12B are explanatory views showing a state when an abnormal stop is detected in the hand position examination;

FIGS. 13A, 13B, 13C, 13D, and 13E are explanatory views showing an operation from detection of a hand shift to a correction of the value of a hand position counter; and

40 FIGS. 14A, 14B, 14C, 14D, and 14E are explanatory views showing an operation from detection of an abnormal stop of the hands to a correction of the value of the hand position counter.

45 DESCRIPTION OF THE PREFERRED
EMBODIMENT

In the following, an embodiment of the present invention will be described with reference to the accompanying drawings.

50 FIG. 1 is a block diagram showing the whole of the electronic timepiece of the embodiment of the present invention, and FIG. 2 is a diagram showing the counters and a data storing section formed on the RAM of the embodiment.

55 The electronic timepiece 1 of this embodiment displays time by rotating a second hand 2, a minute hand 3, and an hour hand 4 (see FIG. 8A) above a number plate. As shown in FIG.

1, the electronic timepiece 1 includes a central processing unit (CPU) 11 performing the whole control of the timepiece 1; an analog block 19 including the plurality of hands (the second hand 2, the minute hand 3, and the hour hand 4) and a mechanism driving these hands 2, 3, and 4 to rotate them; a photodetector 20 performing position detection of the second hand 2; a read only memory (ROM) 12 storing control programs executed by the CPU 11 and control data; a random access memory (RAM) 13 providing the CPU 11 with a working memory space; a power source section 16 supplying each

section with an operating voltage; an antenna 17 and a detector circuit 18 for receiving a standard wave for time correction; an oscillation circuit 14 and a clock division circuit 15 for supplying the CPU 11 with a signal of a predetermined frequency; an illumination section 23 and an illumination driving circuit 22 for illuminating the number plate; a speaker 25 and a buzzer circuit 24 for performing an alarm output; and the like.

The analog block 19 includes the second hand 2, the minute hand 3, the hour hand 4, a stepping motor interlocking these hands 2-4 with one another to perform a stepping drive of them, a train wheel mechanism 30 (see FIG. 3) transmitting a rotational motion of the rotor of the stepping motor to the second hand 2, the minute hand 3, and the hour hand 4 by their respective predetermined rotation speed ratios, and the like.

The stepping motor is supplied with drive pulses from the CPU 11 (drive control section) to rotate the rotor by the step of, e.g., 180°. The stepping motor is configured to generate rotations within the range of from 0° to 180° or the range of from 180° to 360° in accordance with the polarities of the drive pulses. A rotation of the rotor to move the second hand 2 to a position of an odd second within the range of from 0° to 180° will be referred to as an odd step; a rotation of the rotor to move the second hand 2 to a position of an even second within the range of from 180° to 360° will be referred to as an even step; a drive pulse of the polarity of producing a rotation of an odd step will be referred to as an odd pulse; a drive pulse of the polarity of producing a rotation of an even step will be referred to as an even pulse.

The RAM 13 includes at its predetermined regions a timing counter 13a counted up by the CPU 11 on the basis of a divided frequency signal from the clock division circuit 15 to hold the time data indicating the present time; a hand position counter 13b counted up by the CPU 11 on the basis of the number of the drive times of the stepping motor to hold the number of hand position steps indicating the present positions of the second hand 2, the minute hand 3, and the hour hand 4; and a hand position temporal storage section 13c capable of temporarily holding the value (at least the value of hours and minutes by the time scale) of the hand position counter 13b.

The electronic timepiece 1 of this embodiment is configured to interlock the three hands including the second hand 2, the minute hand 3, and the hour hand 4 with one another to rotate them with one stepping motor. The electronic timepiece 1 is, furthermore, configured in such a way that the second hand 2 makes one revolution per minute by 60 steps; the minutes hand 3 makes one revolution per 60 minutes; and the hour hand 4 makes one revolution per 12 hours. The hand position counter 13b, consequently, results in storing counted values indicating "0" to "(60×60×12)-1=43199" according to the number of drive steps of the second hand 2, the minute hand 3, and the hour hand 4.

FIG. 3 shows a front view showing the train wheel mechanism 30, included in the analog block 19 of FIG. 1, and FIG. 4 shows a sectional view showing an arrangement relation among a first detection wheel, a second detection wheel, and the photodetector 20.

The train wheel mechanism 30 is composed of a plurality of gears including a second hand wheel 31, to which the second hand 2 is adhered with a connecting shaft put between them; a minute hand wheel 32, to which the minute hand 3 is adhered with a hollow connecting shaft put between them; an hour hand wheel 33, to which the hour hand 4 is adhered with a hollow connecting shaft put between them; a third wheel 34 transmitting the rotation of the second hand wheel 31 to the minute hand wheel 32 at a rotation speed ratio of "60:1"; a minute wheel 35 transmitting the rotation of the minute hand

wheel 32 to the hour hand wheel 33 at a rotation speed ratio of "12:1"; a drive wheel 36 adhered to the rotor of the stepping motor; a fifth wheel 37 transmitting the rotation of the drive wheel 36 to the second hand wheel 31 at a rotation speed ratio of "30:1"; a first detection wheel 38 rotating at the same rotation speed ratio as that of the second hand wheel 31 to be used for the position detection of the second hand 2; and a second detection wheel 39 for exposing the penetration hole 40 of the first detection wheel 38 only at a necessary step position.

The second hand wheel 31, the minute hand wheel 32, and the hour hand wheel 33 are arranged in such a way that their respective rotating shafts overlap one another on the same shaft line. Then, the train wheel mechanism 30 is configured in such a way that the hollow connecting shaft of the minute hand 3 is inserted into that of the hour hand 4; the connecting shaft of the second hand 2 is inserted into the hollow connecting shaft of the minute hand 3; and these three connecting shafts each rotate on the same shaft line to be configured to transmit these rotations to the second hand 2, the minute hand 3, and the hour hand 4, respectively.

The penetration hole 40 as a section to be detected (a target section) is formed in the first detection wheel 38. The penetration hole 40 is, for example, a through-hole transmitting light therethrough, and the other parts of the first detection wheel 38 is configured to intercept light. A penetration hole 41 is formed in the second detection wheel 39 at a radial position overlapping that of the penetration hole 40 of the first detection wheel 38. The penetration hole 41 is, for example, a through-hole transmitting light therethrough, and the other parts of the second detection wheel 39 is configured to intercept light. The second detection wheel 39 rotates by a relatively large rotation angle, such as 36°, when the first detection wheel 38 rotates by one step (6°). Thereby, when the second hand 2 reaches a detection position (e.g. "00" second position), the two penetration holes 40 and 41 overlap each other at the detection position P (see FIG. 9D "i-3"). On the other hand, when the second hand 2 is situated at a step position before or after the detection position P, the penetration hole 41 of the second detection wheel 39 is largely shifted to be a state in which the penetration hole 40 of the first detection wheel 38 is not exposed at the detection position P (see FIG. 9C "h-3" and FIG. 9E "j-3"). Hence, the train wheel mechanism 30 is configured in such a way that the penetration hole 40 is exposed at the detection position P only by a predetermined step and is hidden from the detection position P before and after the detection position P although the first detection wheel 38 rotates only by a small rotation angle (e.g. 6°).

The photodetector 20 is composed of a light emitting section 20a, such as a light emitting diode, and a light receiving section 20b, such as a phototransistor. These light emitting section 20a and light receiving section 20b are fixed onto the bearing plate of the electronic timepiece 1 with the first detection wheel 38 and the second detection wheel 39 put between the sections 20a and 20b. As shown in FIG. 4, the photodetector 20 is configured in such a way that a light emitted from the light emitting section 20a passes through the penetration holes 40 and 41 to be received by the light receiving section 20b when the penetration holes 40 and 41 overlap each other at the detection position P. The hand position detecting section is configured by including the first detection wheel 38, the second detection wheel 39, and the photodetector 20.

The ROM 12 stores a timing processing program for counting up the timing counter 13a to update time data on the basis of a signal from the clock division circuit 15; a time display processing program for driving the stepping motor at the time

of a carry of one second in synchronization with the time data of the timing counter **13a** to thereby display time with the plurality of hands **2**, **3**, and **4**; a hand position counting processing program for counting up the hand position counter **13b** to update hand position data along with the drive of the stepping motor; a hand position examining processing program for examining whether delays or abnormal stops of the hands **2**, **3**, and **4** have arisen or not at the time of a carry of one minute in synchronization with the time data of the timing counter **13a**; and the like; as the control programs to be executed by the CPU **11**.

Next, the hand position examining processing to be executed in the electronic timepiece **1** having the configuration described above will be described with reference to flow charts and explanatory views.

FIGS. **5-7** are flow charts showing the control procedure of the hand position examining processing to be executed by the CPU **11**. FIGS. **8A-14E** are explanatory views showing the operation contents of the electronic timepiece **1** at the time of the hand position examining processing.

In FIGS. **8A-13E**, “a-1”-“j-1” show the times converted from values of the hand position counter **13b**; “a-2”-“j-2” show positions of the hands **2**, **3**, and **4** on the number plate; and “a-3”-“j-3” show states of the penetration holes **40** and **41**. Moreover, in FIGS. **14A-14E**, “a-1”-“e-1” show values of the timing counter **13a**; “a-2”-“e-2” show the times converted from values of the hand position counter **13b**; “a-3”-“e-3” shows positions of the hands **2**, **3**, and **4** on the number plate; and “a-4”-“e-4” show states of the penetration holes **40** and **41**.

[Hand Shift Check]

The electronic timepiece **1** of this embodiment performs the processing of “hand shift check” once a minute at the time of a normal hand movement displaying time to ascertain whether any delay or abnormal stop of the second hand **2** has arisen or not. The processing of the “hand shift check” constitutes a part of the hand movement examining section (a first examining section). In the processing of the “hand shift check,” the hand position detection is performed twice at two timings in 60 seconds. That is, the electronic timepiece **1** detects whether the penetration holes **40** and **41** are in the state of overlapping each other at the detection position **P** by operating the photodetector **20** at the timing of “00” second, at which the penetration holes **40** and **41** should overlap each other at the detection position **P** in a normal hand movement, and at the timing of “01” second, at which the penetration holes **40** and **41** should not overlap each other completely in the normal hand movement.

The hand position examining processing will now be described with reference to the flow charts and the explanatory views. The CPU **11** starts this hand position examining processing (FIGS. **5-7**) on the basis of a minute carry (carry in minute digits) of the timing counter **13a** in a normal hand movement. When the CPU **11** has started this hand position examining processing, the CPU **11**, first, moves the hand position examining processing to the processing of the “hand shift check,” and, thereby, executes hand shift check once a minute.

When the CPU **11** has moved the hand position examining processing to the processing of the “hand shift check,” the CPU **11**, first, outputs drive pulses to the stepping motor to execute hand movement processing at the time of the minute carry (Step **S1**), and successively makes the photodetector **20** operate to judge whether a light passing through the penetration holes **40** and **41** is detected or not (Step **S2**).

If the light is detected as a result, the CPU **11** waits a second carry (carry in second digits) of the timing counter **13a** (Step

S3). When the second carry occurs, the CPU **11** outputs drive pulses to the stepping motor to execute the hand movement processing at 01 sec (Step **S4**). Successively, the CPU **11** operates the photodetector **20** to judge whether a light passing through the penetration holes **40** and **41** is detected or not (Step **S5**). Because it is normal that no overlapping of the penetration holes **40** and **41** exists at “01” second, if no light is detected here, the CPU **11** regards the state as including no abnormality and ends the hand position examining processing.

FIGS. **8A-8E** and FIGS. **9A-9E** show the operation of the electronic timepiece **1** at the time of a normal hand movement. The CPU **11** starts the hand position examining processing at the timing of “00” second shown in FIG. **8A** “a-1”, “a-2”, and “a-3”, and the CPU **11** performs the detection of the penetration holes **40** and **41** with the photodetector **20** at this timing and the timing of “01” second shown in FIG. **8B** “b-1”, “b-2”, and “b-3”. Then, at the timing of “00” second, the penetration holes **40** and **41** overlap each other at the detection position **P**, and a detection result is detected; and at the time of “01” second, the overlapping of the penetration holes **40** and **41** is removed and the detection result becomes non-detection. The CPU **11** ascertains the normal hand movement of the second hand **2** by this detection pattern, and ends one time of the hand position examining processing.

After that, the CPU **11** does not execute the hand position examining processing in the period of from “02” seconds to “59” seconds shown from FIG. **8C** “c-1”, “c-2”, and “c-3” to FIG. **9C** “h-1”, “h-2”, and “h-3”, and the CPU **11** similarly executes the hand position examining processing at the timings of “00” second and “01” second shown in FIG. **9D** “i-1”, “i-2”, and “i-3” and FIG. **9E** “j-1”, “j-2”, and “j-3”, respectively.

On the other hand, if no light is detected in the light detecting processing (Step **S2**) at the timing of “00” second in the processing of the “hand shift check” described above, it is possible to judge that the second hand **2** is delayed. For example, FIG. **10** shows the case where the second hand **2** is delayed. In this case, when the value of the hand position counter **13b** is “00” second, the penetration holes **40** and **41** do not overlap with each other at the detection position **P**, and consequently the result of the light detecting processing at the “00” second is non-detection, which enables the judgment of a delay of the hand movement.

Accordingly, in this case, the CPU **11** next moves the hand position examining processing to the processing of moving the second hand **2** by fast-forwarding to the position of the “00” second, that is, the processing of “even second position fast-forward check” from Step **S8**.

Moreover, if a light is detected in the light detecting processing (Step **S5**) at the timing of the “01” second after the light has been detected at the timing of the “00” second in the processing of the “hand shift check” described above, it is possible to judge that the second hand **2** has abnormally been stopped at the position of the “00” second. For example, FIGS. **11A** and **11B** show the case where the drive of the stepping motor has stopped owing to the approaching of a magnet **51** when the second hand **2** has been situated at the position of the “00” second. In this case, the penetration holes **40** and **41** are in the state of overlapping with each other at the detection position **P** at both of the timings of the values of the hand position counter **13b** of the “00” second and the “01” second. Consequently, the result of the light detecting processing also at the “01” second indicates light detection, and it is possible to judge that the hand movement has abnormally stopped.

Consequently, in this case, the CPU 11 sets the polarity of the next drive pulse to an even pulse (Step S6) in order to make the value of the hand position counter 13b correspond to the position of the present second hand 2, and makes the hand position temporal storage section 13c store the value of the hand position counter 13b at the present time point (Step S7) in order to easily correct the value of the hand position counter 13b when the normal hand movements of the hands 2, 3, and 4 are next ascertained.

Successively, the CPU 11 moves the hand position examining processing to the processing of "hand movement processing stopping and waiting" from Step S17 in order not to repeatedly perform useless hand movement processing and useless hand position detection processing owing to abnormal stops of the hand movement.

[Even Number Position Fast-Forward Check]

Next, the processing of the "even second position fast-forward check," to which the hand position examining processing is moved when a delay of the hand movement is detected, will be described. This processing is the processing of outputting drive pulses to the stepping motor up to 60 pulses and of performing hand position detection every output of an even pulse to judge whether the second hand 2 comes the position of the "00" second or not. The processing of the "even second position fast-forward check" constitutes a part of the hand movement examining section (a second examining section).

If the hand movement is only temporarily stopped to cause the delay when the delay of the hand movement is detected, the second hand 2 arrives at the position of the "00" second after outputting any one of even pulses by driving the hands 2, 3, and 4 up to 60 steps. Consequently, the state in which the second hand 2 is situated at the position of the "00" second can be found out by making the photodetector 20 operate to perform hand position detection after the outputting of the even pulses. For example, FIG. 13A "a-1", "a-2", and "a-3" to FIG. 13D "d-1", "d-2", "d-3" show an example of this case. As shown in FIGS. 13A-13D, the CPU 11 detects a delay of the hand movement at the timing of the value of the hand position counter 13b of "10:08:00" and moves the hand position examining processing to the processing of the "even second position fast-forward check." After that, the CPU 11 repeats outputting odd pulses and even pulses to advance the hands 2, 3, and 4, and performs hand position detection every outputting an even pulse. Then, the CPU 11 judges that the second hand 2 has reached the position of the "00" second at the timing of the value of the hand position counter 13b of "10:08:10."

On the other hand, if the hands 2, 3, and 4 are abnormally stopped owing to an external factor such as the magnet 51, the second hand 2 remains in the state of being stopped not to return to the position of the "00" second even if the CPU 11 outputs drive pulses for 60 steps to the stepping motor. Consequently, if the CPU 11 performs the hand position detection every even pulse throughout the outputting period of the drive pulses for 60 steps and obtains the results of non-detection to all the hand position detection, then the CPU 11 can judge that the hands 2, 3, and 4 are abnormally stopped. For example, FIGS. 12A and 12B show an example of this case. In the case of FIGS. 12A and 12B, the CPU 11 detects a delay of the hand movement at the timing of the value of the hand position counter 13b of "10:08:00" and moves the hand position examining processing to the processing of the "even second position fast-forward check." After that, the CPU 11 performs hand position detection every outputting an even pulse together with outputting drive pulses, and the CPU 11 is not capable of obtaining the result of light detection even when

the value of the hand position counter 13b becomes "10:09:00" and judges that the hands 2, 3, and 4 have abnormally been being stopped.

The operation of the "even second position fast-forward check" will now be described with reference to the flow chart of FIG. 6. When the CPU 11 has moved the hand position examining processing to the processing of "even second position fast-forward check," the CPU 11, first, sets the polarity of the next drive pulse to that of an odd pulse (Step S8). Next, the CPU 11 stores the value of the hand position counter 13b into the hand position temporal storage section 13c (Step S9) in order to be capable of easily correcting the value of the hand position counter 13b when the normal hand movements of the hands 2, 3, and 4 are next ascertained.

Successively, the CPU 11 initializes a variable Hand_Ct for counting the number of output times of the drive pulses to zero (Step S10) and supply the stepping motor with a drive pulse for one step by a fast-forward period (Step S11) to add "1" to the value of the variable Hand_Ct (Step S12). Successively, the CPU 11 judges whether the drive pulse output at Step S11 is an even pulse or not (Step S13), and returns the hand position examining processing to Step S11 if the judged drive pulse is an odd pulse. On the other hand, if the judged drive pulse is an even pulse, the CPU 11 operates the photodetector 20 to detect the penetration holes 40 and 41 (Step S14). If the CPU 11 detects the penetration holes 40 and 41 as a result, the CPU 11 moves the hand position examining processing to the processing of "odd second position check and hand position counter correction" from Step S23. On the other hand, if the CPU 11 does not detect the penetration holes 40 and 41, the CPU 11 ascertains whether the variable Hand Conn. becomes "60" or not (Step S15), and returns the hand position examining processing to Step S11 if the variable Hand Conn. does not become "60."

Moreover, if the CPU 11 judges that the variable Hand_Ct becomes "60" by the judgment processing at Step S15, the CPU 11 can judge that the fact indicates abnormal stops of the hands 2, 3, and 4, and the CPU 11 accordingly moves the hand position examining processing to the processing of "hand movement processing stopping and waiting" from Step S17. By such processing, the processing operation of the "even second position fast-forward check" mentioned above is realized.

[Odd Second Position Check and Hand Position Counter Correction]

Successively, the processing of "odd second position check and hand position counter correction," to which the hand position examining processing is moved when the hand positions are detected in the processing of the "even second position fast-forward check," will be described. This processing is, as shown in FIGS. 13D "d-1", "d-2", and "d-3" and 13E "e-1", "e-2", and "e-3", the processing of ascertaining whether the second hand 2 is correctly being moved or not by performing the further outputting of the next drive pulse and hand position detection after detecting that the second hand 2 has reached the position of the "00" second, and of correcting the data value of the hand position counter 13b if the second hand 2 has correctly been being moved.

The correction of the data value of the hand position counter 13b is, here, performed on the basis of the next theory. That is, in this electronic timepiece 1, it is not supposed that the hands 2, 3, and 4 shift in their gaining directions, and it is supposed that the hands 2, 3, and 4 once stop owing to an external factor such as a magnet and the hands 2, 3, and 4 thereby shift into their delaying directions.

Consequently, as shown in FIG. 13A "a-1", "a-2", and "a-3", if a positional shift of the second hand 2 is detected in

the processing of “hand shift check,” the hands **2**, **3**, and **4** can be judged that they are situated at positions where the time indicated by them is delayed within one minute from the time indicated by the value of the hand position counter **13b** at that time point. The reason is that the processing of the “hand shift check” is performed every minute. Then, the value of the hand position counter **13b** at this time point is stored in the hand position temporal storage section **13c** by the processing at Steps **S7** and **S9**.

Furthermore, the CPU **11** performs the hand position detection every outputting an even pulse to the stepping motor in the processing of the “even second position fast-forward check” as shown in FIG. **13B** “b-1”, “b-2”, and “b-3” to FIG. **13D** “d-1”, “d-2”, and “d-3” after a positional shift has been detected in the processing of the “hand shift check.” Hence, if the CPU **11** cannot obtain any result of light detection in the hand position detection, it can be judged that the second hand **2** has not moved across the “00” second from the shifted state of the hands **2**, **3**, and **4**. Moreover, as shown in FIG. **13D** (d-1), (d-2), and (d-3), when the second hand **2** is next detected at the position of the “00” second, it can be judged that the hands **2**, **3**, and **4** are situated at the positions indicated by the value of the hand position counter **13b** when the preceding positional shifts have been detected, i.e., the value of the hand position temporal storage section **13c**.

Consequently, as shown in FIG. **13E** “e-1”, “e-2”, and “e-3”, if the CPU **11** has output the next odd pulse in the processing of this “odd second position check and hand position counter correction” and has judged that the second hand **2** has advanced the position of the “01” second, then the CPU **11** reads out the value (“10:08:00” in FIG. **13E**) of the hand position temporal storage section **13c**, and changes the value of the second digit to “01.” After that, the CPU **11** overwrites the hand position counter **13b** with this value to correct the hand position counter **13b**.

The processing of the “odd second position check and hand position counter correction” will now be described with reference to the flow chart of FIG. **7**. When the CPU **11** has moved the hand position examining processing to the processing of the “odd second position check and hand position counter correction,” the CPU **11**, first, outputs a drive pulse for one step to the stepping motor (Step **S23**), and the CPU **11** next makes the photodetector **20** operate to perform hand position detection (Step **S24**). If the second hand **2** has moved to the position of the “01” second and the detection result is non-detection as a result, then the CPU **11** can judge that the second hand **2** has been performing a normal hand movement. Consequently, as described above, the CPU **11** corrects the value of the hand position counter **13b** on the basis of the value of the hand position temporal storage section **13c** (Step **S25**). Then, the CPU **11** next moves the hand position examining processing to the processing of “fast-forward hand position return.”

On the other hand, if the second hand **2** has not moved to the position of the “01” second and the CPU **11** obtains the result of light detection in the hand position detection at Step **S24**, then the CPU **11** can judge that the second hand **2** has abnormally been stopped at the position of the “00” second. Consequently, the CPU **11** returns the hand position examining processing to Step **S6**, and after that, the CPU **11** moves the hand position examining processing to the processing of the “hand movement processing stopping and waiting” from Step **S17**.

[Hand Movement Processing Stopping and Waiting]

Next, the processing of the “hand movement processing stopping and waiting,” to which the CPU **11** moves the hand position examining processing when the hands **2**, **3**, and **4** are

abnormally stopped will be described. The processing of the “hand movement processing stopping and waiting” constitutes a waiting control section. This processing is the processing of coping with abnormal stops of the hands **2**, **3**, and **4** owing to an external factor to spontaneously stop hand movement processing and the processing of hand position detection for little while in order not to bring about useless power consumption and of waiting until the next execution of the processing of hand position detection.

After having waited for a predetermined time by the processing of this “hand movement processing stopping and waiting,” the CPU **11** again performs the processing of the “even second position fast-forward check” to ascertain whether the abnormal stops of the hands **2**, **3**, and **4** have been solved or not. Then, if the CPU **11** judges that the abnormal stops are not solved, then the CPU **11** ends up repeatedly executing this processing of the “hand movement processing stopping and waiting.”

In this processing of the “hand movement processing stopping and waiting,” if the abnormal stops of the hands **2**, **3**, and **4** are not solved and the CPU **11** repeatedly executes this processing of the “hand movement processing stopping and waiting,” the waiting time of this processing is set to gradually lengthen. For example, the waiting time is set to be 5 minutes in a first processing of the “hand movement processing stopping and waiting”, 10 minutes in a second processing, 30 minutes in a third processing, 60 minutes in a fourth processing, 120 minutes in a fifth and after processing, and the like.

This processing of the “hand movement processing stopping and waiting” will be described with reference to the flow chart of FIG. **6**. When the CPU **11** moves the hand position examining processing to this processing of the “hand movement processing stopping and waiting,” the CPU **11**, first, performs the setting of a status flag and the like for temporarily stopping hand movements (Step **S17**), and initializes a variable **Wait_Ct** for counting a waiting time to zero (Step **S18**). Successively, the CPU **11** judges whether there is a minute carry (carry in the minute digits) of the timing counter **13a** or not (Step **S19**). If there is no minute carry, the CPU **11** repeats the judgment processing until a minute carry occurs. On the other hand, if there is a minute carry, the CPU **11** counts up the variable **Wait_Ct** (Step **S20**) and judges whether the variable **Wait_Ct** reaches a set value **X** or not (Step **S21**). The set value **X** is set to be 5 minutes at a first time. If the processing of the “hand movement processing stopping and waiting” is repeatedly executed, the set value **X** will be set according to the number of repeated times. For example, if the number of repeated times is two, the set value **X** will be set to be 10 minutes; if three, then 30 minutes; if four, then 60 minutes; if more than four, then 120 minutes. When the CPU **11** ascertains the solution of a hand shift, the CPU **11** will reset the number of repeated times.

If the variable **Wait_Ct** does not reach the set value **X** as the result of the judgment processing at Step **S21**, the CPU **11** returns the hand position examining processing to Step **S19**. On the other hand, if the variable **Wait_Ct** has reached the set value **X**, the fact indicates a lapse of the waiting time, and the CPU **11** accordingly performs the setting of a status flag and the like for restarting hand movements and the processing of the hand position detection (Step **S22**). Then, the CPU **11** sets the polarity of the next drive pulse to an even pulse (Step **S16**), and moves the hand position examining processing to the processing of the “even second position fast-forward check” from Step **S10**.

FIGS. **14A-14E** show an example of the operation from abnormal stops of the hands **2**, **3**, and **4** owing to the magnet **51** to the correction of the value of the hand position counter

11

13b through the processing of the “hand movement processing stopping and waiting.” As shown in FIGS. 14A-14E, after the CPU 11 has detected the abnormal stops of the hands 2, 3, and 4 by the processing of the “hand shift check” shown in FIG. 14A “a-1”, “a-2”, “a-3”, and “a-4”, and FIG. 14B “b-1”, “b-2”, “b-3”, and “b-4”, the CPU 11 moves the hand position examining processing to the processing of the “hand movement processing stopping and waiting” for 5 minutes, and the magnet 51 is removed during the waiting processing (FIG. 14C “c-1”, “c-2”, “c-3”, “c-4”). Then, when the waiting processing has ended as shown in FIG. 14D “d-1”, “d-2”, “d-3”, and “d-4”, the CPU 11 moves the hand position examining processing to the processing of the “even second position fast-forward check,” and outputs an even pulse and performed hand position detection. The CPU 11 thus detects the fact that the second hand 2 is situated at the position of the “00” second.

At the timing of FIG. 14D “d-1”, “d-2”, “d-3”, and “d-4”, because the second hand 2 is originally situated at the position of the “00” second, the stepping motor, the first detection wheel 38, the second detection wheel 39, and the second hand 2 do not rotate by the output of the even pulse, and thereby it is detected that the second hand 2 is situated at the position of the “00” second at this time point.

Then, at the timing of FIG. 14E “e-1”, “e-2”, “e-3”, and “e-4”, the CPU 11 performs the processing of the “odd second position check and hand position counter correction.” When the CPU 11 judges that the overlapping of the penetration holes 40 and 41 to each other is removed and the second hand 2 has moved to the position of the “01” second, and then the CPU 11 corrects the data value of the hand position counter 13b on the basis of the data value stored in the hand position temporal storage section 13c at the time of detecting the abnormal stops of the hands 2, 3, and 4. The method of the correction of the data value is the same as that described above.

[Fast-Forward Hand Position Return]

Next, the processing of “fast-forward hand position return,” to which the CPU 11 moves the hand position examining processing when the CPU 11 has corrected the data value of the hand position counter 13b. The processing of the “fast-forward hand position return” is the processing performing fast-forward hand movements of the hands 2, 3, and 4 to adjust the position data of the hands 2, 3, and 4 shown by the hand position counter 13b to the time data shown by the timing counter 13a. By the processing, the positional shifts of the hands 2, 3, and 4 from the present time are solved, and the present time shown by the timing counter 13a ends up being displayed with the plurality of hands 2, 3, and 4.

The CPU 11 is also configured as follows: when the CPU 11 performs the fast-forward hand movements of the hands 2, 3, and 4 by the processing of the “fast-forward hand position return,” the CPU 11 performs hand position detection at the timing when the second hand 2 arrives at the position of the “00” second and the timing when the second hand 2 arrives at the position of the “01” second to ascertain whether the hand movement is normally being performed or not similarly to the processing of the “hand shift check.”

The processing of the “fast-forward hand position return” will be described with reference to the flow chart of FIG. 7. When the CPU 11 has moved the hand position examining processing to the processing of the “fast-forward hand position return,” the CPU 11 compares the value of the timing counter 13a to that of the hand position counter 13b to judge whether the positions of the present hands 2, 3, and 4 agree with the present time (Step S26). If the both agree with each other as the result, it can be judged that the hands 2, 3, and 4

12

has moved to the positions of the present time and the correction has been completed, and the CPU 11 accordingly ends this hand position examining processing.

On the other hand, if the both do not agree with each other, the CPU 11 supplies the stepping motor with drive pulses at the period of a fast-forward (Step S27). Next, the CPU 11 judges whether it is the timing when the second hand 2 is supposed to be situated at the position of the “00” second or not on the basis of the data value of the hand position counter 13b (Step S28).

If the timing is not that of the “00” second as the result, the CPU 11 returns the hand position examining processing to Step S26. On the other hand, if the timing is that of the “00” second, the CPU 11 operates the photodetector 20 to perform hand position detection for detecting the overlapping of the penetration holes 40 and 41 to each other (Step S29). Then, if the overlapping is not detected as the result, the CPU 11 judges that a hand shift has again occurred and consequently jumps the hand position examining processing to the processing of the “even second position fast-forward check” from Step S8 again.

Moreover, if the detection result at Step S29 is light detection, the CPU 11 judges whether the present positions of the hands 2, 3, and 4 agree with the present time or not (Step S30), and ends the hand position examining processing as it is if the both agree with each other. On the other hand, if the both do not agree with each other, the CPU 11, first, performs hand movement processing of one step in a fast-forward period to advance the second hand 2 to the position of the “01” second (Step S31). Next, the CPU 11 performs hand position detection for ascertaining whether the second hand 2 has reached the position of the “01” second or not (Step S32). If the detection result is non-detection, the CPU 11 judges that the second hand 2 has normally moved to return the hand position examining processing to Step S26. On the other hand, if the detection result is light detection, the CPU 11 judges that the second hand 2 has abnormally been stopped at the position of the “00” second, and performs the processing at Steps S6 and S7. After that, the CPU 11 moves the hand position examining processing to the processing of the “hand movement processing stopping and waiting.”

If normal hand movements have been performed by the aforesaid loop processing at Steps S26-S28 or Steps S26-S32, the CPU 11 moves the plurality of hands 2, 3, and 4 to the positions indicating the present time by a fast-forward, and ends the hand position examining processing.

As described above, the electronic timepiece 1 of this embodiment moves the hand position examining processing to the processing of the “hand movement processing stopping and waiting” to be in a waiting state only for a predetermined time and to interrupt the output of the drive pulses to the stepping motor and the processing of hand position detection when an abnormal stop of the second hand 2 is detected. Hence, for example, if a strong magnet approaches the electronic timepiece 1 and the hands 2, 3, and 4 fall into abnormal stops for a comparatively long time, the situation in which the output of the drive pulses and the operation of hand position detection are uselessly executed many times to cause a remarkable increase of power consumption can be avoided.

Moreover, the electronic timepiece 1 of this embodiment is configured as follows: when the processing of the “hand shift check” results in light detection at both of the timings of the “00” second and the “01” second, and when the processing of the “even second position fast-forward check” results in no detection of the second hand 2 even though 60 drive pulses have been output, then the electronic timepiece 1 judges that the hands 2, 3, and 4 are abnormally stopped to move the hand

13

position examining processing to the processing of the "hand movement processing stopping and waiting." Hence, when the hands **2**, **3**, and **4** abnormally stop, the electronic timepiece **1** can rapidly detect these abnormal stops to rapidly stop any useless output of drive pulses and the processing of hand position detection.

Moreover, the electronic timepiece **1** is configured as follows: after having released a waiting state in the processing of the "hand movement processing stopping and waiting," the electronic timepiece **1** moves the hand position examining processing to the processing of the "even second position fast-forward check," examines whether the second hand **2** performs a hand movement or not again, and moves the hand position examining processing to the processing of the "hand movement processing stopping and waiting" again to be in the waiting state at the time of judging that the second hand **2** is stopped in this examination again. Consequently, the electronic timepiece **1** is configured to be capable of avoiding the increase of the power consumption thereof by repeating entering the waiting state thereof when the abnormal stops of the hands **2**, **3**, and **4** extends over a long period of time, and the electronic timepiece **1** is configured to ascertain whether the second hand **2** has become capable of performing the hand movement thereof during the repletion of the waiting state or not when the hands **2**, **3**, and **4** have abnormally been stopped only for a short time, and to be capable of rapidly returning the hand movements of the hands **2**, **3**, and **4** to their normal ones when the second hand **2** become capable of performing the hand movement thereof.

Furthermore, because the electronic timepiece **1** is designed to gradually lengthen the waiting times from first one to fifth one when the processing of the "hand movement processing stopping and waiting" is repeated, the electronic timepiece **1** can perform the ascertainment of the hand movement of the second hand **2** during waiting processing comparatively early to enable the rapid restart of the hand movement processing of the second hand **2** when an abnormal stop thereof is released in a short period. Moreover, when abnormal stops of the hands **2**, **3**, and **4** extend over a long period of time, the electronic timepiece **1** is configured to reduce the execution frequency of the hand movement ascertainment of the second hand **2** during the waiting processing to achieve the further reduction of the power consumption.

Moreover, because the electronic timepiece **1** of this embodiment is configured to form the penetration holes **40** and **41** in the first detection wheel **38** and the second detection wheel **39**, respectively, detect these penetration holes **40** and **41** with the photodetector **20**, and thereby judge whether the second hand **2** is situated at the detection position **P** (for example, "00" second position) or not, the electronic timepiece **1** is configured to be hard to be influenced by an external environment and to be capable of performing the sure position detection of the second hand **2**.

Incidentally, the present invention is not limited to the embodiment described above, but can variously be changed. For example, although the electronic timepiece **1** of the type of driving the second hand **2**, the minute hand **3**, and the hour hand **4** in conjunction with one another with one stepping motor has been shown in the embodiment described above, for example, the present invention can also be applied to the electronic timepiece **1** of the type of independently driving the second hand **2**, the minute hand **3**, and the hour hand **4** with three stepping motors, respectively. In this case, it is preferable to configure the electronic timepiece **1** to be provided with a mechanism for examining the normal hand movements of all of or any one of the second hand **2**, the minute hand **3**, and the hour hand **4**, and to enter an waiting

14

state thereof by interrupting the supply of drive pulses to the three stepping motors when an abnormal stop of any one of the hands **2**, **3**, and **4** is detected.

Moreover, although the embodiment described above is provided with the penetration hole **40**, as the section to be detected, formed in the first detection wheel **38** to perform the position detection of the second hand **2** by detecting the penetration hole **40** with the photointerrupter type photodetector **20**, it is also possible to configure the embodiment to 10 form the section to be detected to be a reflecting section and to perform the position detection of the second hand **2** by detecting the reflecting section with a photoreflector type photodetector.

In addition, the details shown in the embodiment, such as 15 the detection method of stops of the hands **2**, **3**, and **4**, and concrete examples of setting times for entering a waiting state, can suitably be changed without departing from the scope and sprit of the present invention.

What is claimed is:

1. An electronic timepiece, comprising:
hands which indicate time to display the time;
a stepping motor which performs a stepping drive of the hands;

a drive control section which supplies the stepping motor with drive pulses;

a hand movement examining section which examines whether the hands are moving or not; and

a waiting control section which temporarily interrupts a supply of the drive pulses by the drive control section to be in a waiting state, when the hand movement examining section judges that the hands are stopped, wherein the supply of the drive pulses by the drive control section and an examination of whether the hands are moving or not by the hand movement examining section are respectively restarted, after the waiting control section has released the waiting state.

2. The electronic timepiece according to claim 1, wherein the hands include a second hand;
the electronic timepiece further comprises a hand position detecting section which detects whether the second hand is situated at a predetermined position or not; and
the hand movement examining section includes:

a first examining section which examines whether the second hand has passed the predetermined position or not by making the hand position detecting section detect the second hand at a plurality of timings at which the second hand is supposed to pass the predetermined position, when a hand movement is normal; and

a second examining section which examines whether the second hand has passed the predetermined position or not by making the hand position detecting section detect the second hand at each time when the drive control section supplies the drive pulses for one step or for two steps, when a position of the second hand is unknown, wherein

the hand examining section judges that the second hand is stopped when the second hand is detected at the predetermined position at the plurality of timings in examination processing by the first examining section, and when the secondhand is not detected in examination processing by the second examining section even when the drive pulses for one round of the second hand have been supplied.

3. The electronic timepiece according to claim 2, wherein the hand position detecting section includes:

15

a gear which rotates in conjunction with the second hand,
and includes a target section; and
a photodetector which radiates a light to the gear at a
predetermined detection position so as to identify a state
in which the target section appears at the detection position
and a state in which the target section is hidden from
the detection position. 5

4. The electronic timepiece according to claim 1, wherein
the waiting control section temporarily interrupts the supply
of the drive pulses by the drive control section again 10
to be in a subsequent waiting state, when the hands are
judged to be stopped again in examination processing by
the hand movement examining section after the waiting
state has been released.

5. The electronic timepiece according to claim 4, wherein 15
the waiting control section sets a period of the subsequent
waiting state to be longer than a period of the previous
waiting state, when the electronic timepiece moves to
the subsequent waiting state.

16
